UNITED STATES PATENT OFFICE.

KEZIAH WAPLES, OF WOODBURY, NEW JERSEY.

SILVER-CLEANING OUTFIT.

Application filed October 25, 1927. Serial No. 228,523.

My invention relates to new and useful improvements in a silver cleaning outfit and a compound for use in connection therewith, and has for its object to provide a liquid measuring receptacle and a powder containing and measuring secondary bottom, composed of a metal subject to attack by a compound sodium solution.

A further object of my invention is to utilize a compound sodium solution for attacking the secondary bottom for producing a chemical action upon silverware or other articles when immersed in the solution produced in the receptacle.

With these and other ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a central section of my improved outfit.

Fig. 2, is a plan view of the secondary bottom.

In carrying out the invention as herein embodied, 11 represents a receptacle which may be made of any suitable material not subject to chemical attack of sodium solutions, and this receptacle has a series of grooves or ribs 12 around its walls so spaced as to serve as a measure for liquid introduced within said receptacle for the purpose hereinafter set forth.

13 represents a secondary bottom which is in the form of an inverted pan adapted to rest upon the bottom 14 of the receptacle, the lower edge of the side walls of said secondary bottom being intended to fit snugly against the side walls of the receptacle, as clearly shown in Fig. 1. This secondary bottom has formed therein the depressions 15 which serve as pockets or containers for holding the active material, and these containers are perforated, as indicated at 16.

The active chemical compound best adapted for use in my improved outfit consists of two parts of bicarbonate of soda and one part of chloride of sodium or common table salt, and in practice, these are thoroughly mechanically mixed.

Each of the containers 15 is of the proper

capacity to hold the amount of the active compound to produce the proper solution. The amount of water is determined by the first groove or rib around the receptacle so that when a small number of small articles, such as spoons and forks are to be cleaned, one of the containers is filled with the active compound and sufficient water introduced in the receptacle to bring the level of said water to the first groove 12; but when a larger number of articles are to be cleaned or articles of larger size, then two of the containers are filled with the active compound, and water is introduced into the receptacle up to the second groove 12, and where a still greater number of articles or still larger articles are to be treated, then all of the containers are filled with the active compound and sufficient water introduced into the receptacle to bring the water level up to the top groove 12. This provides for accuracy in the measurement of both the amount of active compound to be used and the water for the dissolving of the same. This renders the outfit both convenient and effective for use by the ordinary housewife.

The active compound when placed in the containers and water has been introduced in the receptacle will gradually dissolve forming a solution, which will attack the metal of the false bottom, the latter being preferably aluminum; which solution will set up a chemical action upon the silverware submerged in the solution, and quickly clean the surfaces of said ware without the necessity of scrubbing or other abrasing.

The properties in the containers permit the concentrated solution to pass into the space enclosed by the secondary bottom since this solution has a greater specific gravity than the water, where it will be retained against rapid circulation in the body of the water, and therefore will serve to gradually feed the water with the active element, and prevent any undue chemical attack upon articles being cleaned, avoiding all danger of injuring these articles.

Of course I do not wish to be limited to the exact details of construction as herein shown as these may be varied within the limits of the appended claims without departing from the spirit of my invention.

Having thus fully described my invention, what I claim as new and useful is:

1. The herein described combination of a receptacle having measuring lines there-around, and a secondary bottom of alumi-

num, said bottom having perforated containers therein for holding and measuring an active chemical compound.

2. The herein described combination of a receptacle resistant to the action of a sodium solution, measuring lines formed around said receptacle, a secondary bottom of aluminum, and containers formed in said bottom for

holding and measuring an active material, the capacity of said containers having a definite relation to the measuring lines upon the receptacle. 10

In testimony whereof, I have hereunto affixed my signature.

KEZIAH WAPLES.
